Attorneys.

UNITED STATES PATENT OFFICE

MARTIN F. CONNELL, OF HOLLISTON, MASSACHUSETTS

ATTACHMENT FOR VIOLINS

Application filed December 4, 1928. Serial No. 323,761.

This invention relates to attachments for violins for supporting the violin upon the player's shoulder comfortably and naturally and so that the hard edges of the violin will not come in contact with the player's clothing.

It is common for a violin player to hold the violin against his shoulder by pressing his chin upon a chin rest provided upon the top surface of the violin and steadying the instrument with one hand. It is difficult to support a violin in this manner for any length of time without injury to the player's shoulder. It often happens that the skin upon the player's shoulder becomes blistered and broken or irritated to such an extent as to cause the player discomfort. In order to overcome these difficulties the player has interposed a pad between the violin and shoulder. However, these pads often work down upon the nerve centre below the player's shoulder blade causing the player great discomfort. Furthermore, it is extremely difficult when using such pads to support the violin so as to prevent the violin taking a lopsided position. The effort exerted for this purpose distracts the player's attention from his playing and often causes neuritis of the arm holding the violin.

It is an object of the present invention to provide a shoulder rest for a violin which will protect the player's shoulder and enable the player to support the violin with ease and overcome the tendencies for the violin to assume a lopsided position and at the same time assure the player great freedom during playing.

Another object of the invention is to provide an attachment combining a shoulder rest and clothes protector of light weight which will effectively prevent the hard edges of the violin coming in contact with the player's clothing.

The invention will be more clearly understood from the following description in conjunction with the accompanying drawings; in which,

Fig. 1 is a fragmentary perspective view of the rear portion of a violin embodying the attachment of the invention.

Fig. 2 is a perspective view of the attachment as viewed from the front thereof.

Fig. 3 is a rear elevational view of the same.

Fig. 4 is a view of the attachment looking at the bottom thereof.

Fig. 5 is a perspective view of a frame embodied in the attachment.

Figs. 6 and 7 are sectional views taken upon the line 6—6 and 7—7 of Fig. 3 and

Fig. 8 is a plan view of the attachment.

Before explaining in detail the present invention, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended as considered in view of the prior art and the requirement thereof.

The attachment of the invention comprises a shoulder rest 10 and a shield portion 11 adapted to shield an end portion of a violin. The embodiment of the attachment of the invention illustrated in the accompanying drawings comprises a frame 14, preferably, of skeleton form including a substantially T-shaped portion 15 and a substantially rectangular portion 16 having arms 17 extending therefrom in opposite directions. The portion 16 of the frame is folded along the line *a* to a position substantially perpendicular to the plane of the portion 15 and is given substantially the curvature of the end of a violin, as is clearly shown in Figs. 4 and 8. A suitably shaped pad 18 is secured, as by cement, to the lower surface of the frame portion 15. The pad 18 is constructed of a relatively soft composition, such as pressed felt, tapered from one longitudinal edge towards the other and its lower surface is provided with a concave portion 20. Preferably the top surface of the frame portion 15 is covered with a layer of fabric 21 which is secured thereto, as by a suitable cement. The

entire body is then covered by a finishing fabric 22, such as velvet, the front layer of which is provided with openings 23 through which the arms 17 extend. Preferably, the 5 arms 17 are covered with leather or other protective coating so they will not injure the finish of the violin.

A conventional type of violin 25 is illustrated in Fig. 1 and includes a tail gut 26 which extends from the top surface of the 10 violin down over the end and is secured to a pin 27 fixed in the end face of the violin. A chin rest 28 is secured upon the end portion of the violin by suitable clamps 29 connected 15 with the chin rest 28 by screws 30. The attachment of the invention is readily secured to the violin by slipping one of the arms 17 between the tail gut 26 and the end face of the violin while slipping the other arm 17 20 between the end face of the violin and one of the screws 30.

The attachment of the invention forms a unit embodying a shoulder pad which is shaped to fit firmly against the player's 25 shoulder, the convex portion 20 thereof being arranged transversely of the pad so as to fit over the player's shoulder blade while the thicker outer edges rest in hollows on opposite sides thereof. Thus, the shoulder 30 rest provides a rigid support for the violin so as to overcome any tendency of the violin to assume a lopsided position. As a result it is possible for the player to support the violin upon his shoulder with ease by merely 35 pressing with his chin against the chin rest and without the additional support of one of his arms thereby affording greater freedom during playing. The shield portion 11 of the attachment effectively protects the 40 player's clothing by preventing the tail gut pin 27 and the screws 30 or other hard edges of the violin coming in contact with the player's clothing. The shoulder rest, preferably, is contracted relatively narrow so as not to 45 extend to the vibrating portion of the violin 100 to interfere with the tone of the instrument.

What I claim is:

1. An attachment for a violin comprising a shoulder rest and a shield for an end face 50 of the violin, a skeleton sheet metal frame bent to provide perpendicular portions for supporting respectively said shield and shoulder rest, and means for securing said frame to a violin.

55 2. An attachment for a violin comprising a shoulder rest and a shield for an end face of a violin, and a skeleton sheet metal frame bent to provide perpendicular portions for supporting respectively said shield and shoulder rest, the shield supporting portion 60 of said frame having arms extending inwardly in substantially its own plane for securing said frame to a violin.

3. An attachment for a violin comprising 65 a shoulder rest and a shield for an end face

of a violin, and a skeleton sheet metal frame bent to provide perpendicular portions, a shield supported on one of said portions, a shoulder rest pad supported on the other of said portions having a lower transverse concave surface, and means for securing said frame to a violin.

In testimony whereof I affix my signature.

MARTIN F. CONNELL.
